DESCRIPTION

(56) **References Cited**

FIG. 1 is a front, left-side perspective view of our new design.

U.S. PATENT DOCUMENTS

FIG. 2 is a front view thereof.

FIG. 3 is a rear view thereof.

FIG. 4 is a right-side view thereof.

FIG. 5 is a left-side view thereof.

FIG. 6 is a top view thereof; and,

FIG. 7 is a bottom view thereof.

The short broken lines showing elements of the shoe last in the drawings illustrate features of the article of manufacture that form no part of the claimed design. The broken lines consisting of dot-dash lines are boundary lines that show that the claimed design extends to the boundary line, but does not include the boundary line.
